CARBURETED WATER GAS PROCESS

John S. Haug and Harutyun G. Terzian, Philadelphia, and Joseph A. Perry, Swarthmore, Pa., assignors to The United Gas Improvement Company, Philadelphia, Pa., a corporation of Pennsylvania

Application August 29, 1932, Serial No. 630,782

2 Claims. (Cl. 48—205)

The present invention relates to the manufacture of mixed oil gas and water gas.

The principal object of the present invention is to provide a new and improved method of making combustible gas of relatively high calorific power as compared with ordinary carbureted water gas and which may be matchable with such high calorific power gas as natural gas, or which may be mixed in large proportion with natural gas and burned satisfactorily in burners adjusted for natural gas.

By matchable is meant that the calorific power and specific gravity of the gas are such that it may be substituted 100 per centum for natural gas without necessitating changes in burner adjustment. By ability to be mixed with natural gas is meant the ability to mix over fifty per centum of the manufactured gas with the natural gas without requiring burner readjustments.

20 The calorific power of natural gas is in the neighborhood of 1100 B. t. u. per cubic foot and its specific gravity is in the neighborhood of 0.65.

The manufacture of such a gas requires the 25 production of more oil gas of high calorific power per unit of finished gas than is required in ordinary carbureted water gas practice in order to furnish the high calorific power. In order to furnish the required specific gravity a larger proportion of 30 hydrogen must be present to offset the tendency of the increased quantity of rich oil to raise the specific gravity.

The invention will be described in connection 35 with the attached drawing which forms a part of this specification and which illustrates the apparatus of the invention, in partial elevation and partial vertical cross section.

Referring to the drawing:

1 indicates a generator, provided with the porous ignited fuel bed 2. 3 is an air supply means for up air blasting. 4 is an air supply means for providing secondary air, which may also be used for down air blasting and which leads into the generator through bustle pipe 5 and ports 6. 7 is a steam supply means for up steaming and 8 a steam supply means for down steaming. 9 is an oil supply means for spraying oil onto the top of the fuel bed. 10 is a gas offtake provided with valve 11 leading from the base of the generator 50 to the wash box 12.

The generator is connected at the upper portion with the upper portion of the carbureter 13, by the connection 14 provided with valve 15, and at its lower portion is connected with the lower 55 portion of the carbureter by the connection 16

provided with valve 17. The carbureter is provided with the oil supply means 18 which includes a spray for spraying oil into the carbureter. The carbureter is preferably provided with checkerbrick 19, though under certain conditions it may be desirable to employ an empty carbureter. The carbureter is connected with the superheater 20 by the connection 21. The superheater is provided with checkerbrick indicated at 22. 23 is the stack valve. Connection 24 leads from the 10 superheater, through valve 25 to the wash box 26. 27 is the gas offtake from the wash box 26 and leads through valve 28 to storage or other disposal. The gas offtake 29 controlled by valve 30, leads to storage or other disposal, from wash box 12, 15 the gas passing out from wash box 12 is united with that passing from wash box 26 as indicated diagrammatically by the line 31.

The carbureter may also be provided with the gas offtake 33 which leads through valve 34 to 20 the wash box 26. 35 is an oil supply means including a spray for spraying oil into the superheater. 36 is a steam supply means for supplying steam to the superheater. 37 is a steam supply to the carbureter. 38 is a secondary air 25 supply to the carbureter.

In operation, the fuel bed is blasted with air supplied at 3, storing heat in the body of the fuel bed. The resultant producer gas is burned with secondary air supplied through 4, heating the 30 top of the fuel bed and storing heat in the walls of the space above it. The blast gases pass through connection 14, carbureter 13, connection 21, and superheater 20 to the stack, storing heat in the carbureter and superheater. 35

During this step valve 17 is closed and valves 15 and 23 are open.

A short steam purge is then made with steam admitted at 7.

After the purge, with valves 17, 11, 23 and 34 40 shut and valves 15, 25 and 28 open, an uprun is made with steam supplied at 7. Oil is sprayed simultaneously through oil supply means 9 onto the top of the fuel bed and the oil vaporized by the heat stored in the top of the fuel bed and in the walls of the top of the fuel chamber. Simultaneously oil is sprayed into the carbureter through oil supply means 18, and vaporized therein. The oil vapors from the generator together 50 with the water gas produced by the uprun steam pass through the carbureter, with the oil vapors produced in the carbureter, and thence through the superheater where the fixing of the oil gas is completed. The resultant gas passes through 55

connection 24 to wash box 26 and thence through lines 27 and 31 to storage.

A down run is now made with valves 15, 11, 23 and 34 shut and valves 17, 25 and 28 open. Steam 5 and oil are introduced to the top of the generator through supplies 8 and 9 respectively. The oil is vaporized on the top of the fuel bed and the oil vapors pass with the steam through the fuel bed where the oil vapors are cracked to gas consisting largely of hydrogen and methane, 10 depositing the bulk of the carbon liberated by the cracking upon the surfaces of the fuel. The resultant gas passes through connection 16 and through the base of the carbureter to the super- 15 heater. At the same time oil with some steam is admitted to the top of the carbureter through oil supply means 18 and steam supply means 31. This oil is vaporized in the carbureter and the resultant oil vapors are carried by the steam 20 through the carbureter joining the reformed gas coming from the base of the generator and passing with it through the superheater to the wash box 26 and thence to storage.

The cracking operation in the fuel bed has a 25 tendency to produce a stiff pitch which makes a very troublesome deposit in take off pipes and wash boxes on cooling. The oil vaporization in the carbureter and fixing in the superheater where the cracking is not as severe as in the fuel bed 30 produces a fluid tar. The leading of the reformed gas while hot into the base of the carbureter to join the oil gas produced in the carbureter and superheater, obviates the trouble from pitch as the tar produced in these vessels renders the pitch 35 sufficiently fluid. After the down run a short purge may be made and the cycle repeated.

In making high calorific power gas of specific 40 gravity in the neighborhood of 0.65, a large amount of blue water gas is not desired in the finished gas. Therefore the steam admitted during the runs may be limited to that required to furnish a carrying vehicle for the oil vapors and to control the temperature of the fuel bed so as to avoid excessive space cracking with the consequent carrying out of the fuel bed of large quantities 45 of lamp black on the down run.

To control the fuel bed temperature without adding to the blue water gas in the finished gas, steam may be admitted during the air blast and 50 the resultant water gas burned with the blast gases. This has the merit of furnishing additional heat for oil vaporization.

As an alternative, in controlling the temperature of the fuel bed without increasing the quantity 55 of blue water gas in the finished gas, a separate steam run may be made and the resultant blue water gas burned to furnish additional heat for oil vaporization.

As another method of furnishing additional heat 60 for the oil vaporization, during the heating up operation oil or tar may be admitted to the carbureter top through 18 and burned with air supplied through 38. Oil and tar may also be burned in the top of the generator, by admitting oil or tar through 9 and air through 4.

In the foregoing description it is stated that 65 during the above operations the valve 34 is closed. If the cycle is confined to the foregoing steps the connection 33 and the valve 34 may be omitted. 70 However at the end of the run in order to recuperate heat carried to the superheater top, with valves 15, 11, 23 and 25 closed and valves 17 and 34 open, oil may be admitted to the superheater top through oil supply means 35, together with 75 some steam as a carrying medium through steam

supply means 36. The oil is vaporized in the superheater top and the resultant oil vapors are fixed in passing down through the superheater and up through the carbureter. At the same time oil and steam may be admitted to the generator 5 top and the oil vaporized on the top of the fuel bed and the resultant vapors cracked in the fuel bed, the reformed gas passing through connection 16 and up through the carbureter together with the oil gas from the superheater, the mixed 10 gases passing to wash box 26 by way of connection 33 and thence through connection 27 and 31 to storage.

The above operation has the advantage of returning heat from the top of the superheater to 15 ward the carbureter, at the same time vaporizing additional oil, and without reducing the capacity of the fuel bed for cracking still further oil simultaneously.

In all of the above operations the connection 20 10, valve 11, wash box 12, offtake 29, valve 30 and line 31 are not needed and may be omitted. However as an alternative in recuperating the heat from the top of the superheater, at the end of the run, and employing these means, with 25 valves 25, 34, 23 and 15 closed and valves 11, 30 and 17 open, oil and steam may be simultaneously admitted through 35 and 36 respectively to the superheater, through 18 and 37 respectively to the carbureter and through 9 and 8 respectively to the generator. The resultant oil gas passes from the bases of the superheater and carbureter to the base of the generator where it mixes with the reformed gas resulting from 30 passage through the fuel bed, the mixed gases 35 passing to the wash box 12 through connection 10 and thence through connections 29 and 31 to storage.

In the above operations the air blast may be 40 reversed by employing the secondary air supply 4 as a primary air supply for down blasting, the resultant blast gases passing through connection 16 to the base of the superheater and through the superheater to the stack.

The invention provides for relatively inexpensive changes to an ordinary carbureted water gas set whereby its capacity for vaporizing, fixing and reforming oil is greatly increased. Of especial importance in this respect is the combination of the valved bottom connections leading from the generator to the carbureter and the valved connection between the tops of these vessels. Many of the above advantages would be secured by a valved connection between the bottom of the generator and the bottom of the superheater instead of the direct connection between the bottoms of the generator and carbureter, and this is considered to be within the scope of the invention.

It will be obvious that in the above operations 60 in which the oil gas from the carbureter and superheater and the reformed gas from the generator may pass together to either of the two wash boxes, that one wash box might be employed instead of two.

The fuel bed employed is preferably of coke, although very little of such fuel is consumed compared to ordinary carbureted water gas practice. The carbon liberated in cracking the oil vapors and oil gas in their passage through the 70 fuel bed is largely deposited on the coke and furnishes the bulk of the fuel required for the heating and the generation of water gas. However, a fuel bed may be provided by depositing such carbon on a heated bed of broken refrac- 75

tory, and such a fuel bed is considered within the scope of this invention.

The checkerbrick 19 or the walls of an empty carbureter form heat storage material.

5 We do not intend to be limited in the practice of our invention save as the scope of the prior art and of the attached claims may require.

We claim:

1. A process of manufacturing combustible gas as practiced in a set including a generator containing an ignited fuel bed, a carbureter, and a superheater, said process including the following steps: air blasting said ignited fuel bed, burning the resulting blast gases, and storing the heat 10 of said combustion in the top of said fuel bed, in the top of said generator, in said carbureter, and in said superheater; and another step being introducing liquid hydrocarbon to the top of said generator, vaporizing said hydrocarbon there, 15 passing the resulting gas down through the fuel bed, cracking said gas in the fuel bed, passing the cracked gas into and up through the carbureter, simultaneously introducing liquid hydrocarbon to the top of the superheater, vaporizing said liquid hydrocarbon there, passing the resulting hydrocarbon gas down through the superheater, conducting said hydrocarbon gas to the base of the generator, simultaneously introducing liquid hydrocarbon to the top of the superheater, vaporizing said hydrocarbon there, passing the resulting hydrocarbon gas down through the superheater, conducting said hydrocarbon gas to the base of the generator, mixing said gases from said generator, from 20 said carbureter, and from said superheater, and 25 leading off the mixture of said gases to storage.
